UNITED STATES PATENT OFFICE.

CYRUS T. WHALEY, OF NORFOLK, VIRGINIA.

TROLLEY GUARD FOR TUNNELS.

1,416,536.

Specification of Letters Patent. Patented May 16, 1922.

Application filed October 17, 1921. Serial No. 503,055.

To all whom it may concern:

Be it known that I, CYRUS T. WHALEY, a citizen of the United States, residing at Norfolk, in the county of Norfolk and State 5 of Virginia, have invented certain new and useful Improvements in Trolley Guards for Tunnels, of which the following is a specification.

This invention relates to trolley wheel 10 guards and has special reference to a trolley wheel guard particularly for use in connection with tunnels, under bridges and trestles and in other like situations.

One important object of the invention is 15 to provide an improved, simple and economical form of guard or guide which will ensure the movement of a trolley in constant electrical contact throughout the length of the device.

20 A second important object of the invention is to provide an improved device of this character wherein the trolley will be in electrical contact with the guide itself, the wire being supported on the guide so as to 25 feed current to the latter by being arranged exteriorly of said guide.

With the above and other objects in view, the invention consists in general of certain 30 novel details of construction and combinations of parts hereinafter fully described, illustrated in the accompanying drawings, and specifically claimed.

In the accompanying drawings, like characters of reference indicate like parts in the 35 several views, and:—

Figure 1 is a perspective view of the improved device showing a portion of the entering end thereof.

Figure 2 is a similar view showing the 40 opposite end thereof.

Figure 3 is a transverse section there- 45 through.

Figure 4 is a transverse section showing a slight modification of the device.

50 In the invention as herein illustrated there is provided an inverted U-shape trough or channel forming the guide or guard and having a top wall 10 and side walls 11. At the entering end this top wall is curved up- 55 ward as shown at 12 and the side walls are flared outwardly as shown at 13. At the opposite or exit end the top wall projects slightly beyond the side walls and has its corners bent down as at 14. The top and side walls may be either integral as shown

in Figure 3 or may be made of three separate plates as shown in Figure 4, being secured in each instance to an inverted U-shaped bracket 15 conforming in shape to the top and side walls. Any required number of these brackets may be used between the two ends and each of the brackets is provided with an outwardly and upwardly extending lug 16 at each corner. Each lug is provided with an eye 17 in its end for the attachment of the usual suspension wires, and one of the lugs has in addition to this eye an opening 18 wherethrough leads the trolley or feeder wire 19. This wire also passes through an opening 20 in the up- 60 turned top 12 at each end so that the bottom of the wire lies in the same plane as the under side of this top. By means of this construction if the trolley approaches the guide it will run smoothly off the wire onto 65 the top of the guide and, on arriving at the other end, the down turned corners 14 will guide the trolley back onto the wire 19. Thus the guard carrying the trolley may run 70 through the tunnel without any attention 75 being paid to the trolley and without the necessity of either placing the trolley within the guide on approaching the latter or placing it on the wire after leaving the guide.

There has thus been provided a simple 80 and efficient device of the kind described and for the purposes specified.

Having thus described the invention, what is claimed as new, is:—

1. A trolley wheel guide of the class de- 90 scribed consisting of an inverted U-shape member having a flaring inlet end and a contracted outlet end.

2. A trolley guide of the class described comprising an inverted U-shaped trough, 95 bracket supporting said trough of inverted U-shape and engaging the sides and top of the trough, and lugs projecting from said bracket and provided with terminal eyes for the reception of suspension wires, one of said 100 lugs on each bracket being further provided with an opening for the reception of a feeder wire.

3. A trolley guide of the class described comprising an inverted U-shaped trough, 105 bracket supporting said trough of inverted U-shape and engaging the sides and top of the trough, and lugs projecting from said bracket and provided with terminal eyes for the reception of suspension wires, one of 110

said lugs on each bracket being further provided with an opening for the reception of a feeder wire, the inlet end of said trough having its top flaring upwardly and provided with an opening for the reception of the wire and having its sides flaring outwardly, the outlet end of said trough having

its top projecting beyond the sides and having the corners of the top turned downwardly to guide the trolley on said wire. 10

In testimony whereof I affix my signature.

CYRUS T. WHALEY.
